(57) **CLAIM**

The ornamental design for a bicycle pedal strap, as shown and described.

DESCRIPTION

FIG. 1 is a top, front and right side perspective view of the bicycle pedal strap showing my new design;

FIG. 2 is a top plan view thereof;

FIG. 3 is a bottom plan view thereof;

FIG. 4 is an enlarged right side elevation view thereof;

FIG. 5 is an enlarged left side elevation view thereof;

FIG. 6 is a front elevation view thereof; and,

FIG. 7 is a rear elevation view thereof.

The broken lines in the drawing indicate boundaries that form no part of the design to be patented.
